Primary Examiner — John Windmuller*Assistant Examiner* — John R Yeh(74) *Attorney, Agent, or Firm* — Rabin & Berdo, P.C.(57) **CLAIM**

The ornamental design for a wire gripper, as shown and described.

DESCRIPTION

FIG. 1 is a front view of the wire gripper;

FIG. 2 is rear view thereof;

FIG. 3 is a top view thereof;

FIG. 4 is a bottom view thereof;

FIG. 5 is a right side view thereof;

FIG. 6 is a left side view thereof;

FIG. 7 is a perspective view thereof;

FIG. 8 is a reference view showing the wire gripper in use; and,

FIG. 9 is a reference view of the wire gripper in use in an alternate position.

The broken lines in the figures represent environment and portions of the wire gripper that form no part of the claimed design.
